UNITED STATES PATENT OFFICE.

UDOLPHO SNEAD, OF LOUISVILLE, KENTUCKY.

POLE FOR ELECTRIC WIRES.

SPECIFICATION forming part of Letters Patent No. 404,232, dated May 28, 1889.

Application filed January 28, 1889. Serial No. 297,892. (No model.)

To all whom it may concern.

Be it known that I, UDOLPHO SNEAD, a citizen of the United States, residing at Louisville, in the county of Jefferson and State of Kentucky, have invented certain new and useful Improvements in Poles for Electric Wires; and I do hereby declare the following to be a full, clear, and exact description of the invention, such as will enable others skilled in the art to which it appertains to make and use the same.

My invention relates to the construction of iron supports for the connecting-wires of electric apparatus—such as telegraphs, electric lights, and telephones—and for analogous purposes—such as flag-staffs and the like—and its object is to give durability and sightlessness combined with strength and lightness. To this end I construct my improved pole of a cast-iron base, an open wrought-iron column, and a cast or malleable iron top, as herein-after described.

In the drawings, in which like letters indicate like parts, Figure 1 is a front elevation 25 of a form of my improved pole in which the wrought-iron portion is composed of two channel-irons. Fig. 2 is a section of the same through the line *a a*. Fig. 3 is a section of the same through the line *b b*. Fig. 4 is a 30 side elevation of the same. Fig. 5 is an elevation of a form of my improved pole in which the wrought-iron portion is composed of four iron rods and the cast-iron base is cylindricical. Fig. 6 is a section of the same 35 through the line *c c*. Fig. 7 is an enlarged view of the top, with cross-piece carrying insulated connections for the wires and a ratchet, pawl, and drum for tightening the cross-wires of electric railways. Fig. 8 illustrates the insulated bolts, *r* being a rubber sleeve.

A is a cast-iron base, which I prefer to make hollow for lightness and economy, and furnished in the part beneath the surface of 45 the ground with the openings *d*, to more securely hold the grouting. This base may be provided with braces *e* to give it greater support, and it is prolonged above the molding *f*, on which the wrought part of the pole rests, 50 and to this extension the wrought portion is secured—as by being riveted, bolted, screwed, or the like.

B is the wrought-iron part of my improvement, and is securely fastened to the part *g* of the base, and is firmly held together by the 55 wrought-iron bar *h*, which runs in an angular or spiral manner between the bars or rods *i*, and is secured to them by the rivets *j*. It is obvious that the bars or rods *i* may be of different forms—of angle-irons, channel or 60 *T* irons, or of flat or round or half-round bars—and vary in number and in the form in which they may be set in the column without affecting the principle of my invention.

C is the top of the pole, which I prefer to 65 make of cast or malleable iron. It carries the cross-piece *k*, of any suitable material, to support the insulators *l*, and is provided with the drum and ratchet *m* and the pawl *n*, for tightening the cross-wires in electric railways, the insulators *l* being intended for the support of electric wires extended on the 70 poles. The top *C* is also furnished with the flanges *o*, which rest on the insulating material, *q*, and are connected, by means of insulated bolts *r*, with the plate *p*, which covers the wrought part *B* of the pole.

I propose to use wood or rubber for the insulating material, *q*, and to insulate the bolts *r* by means of a hard-rubber casing around 80 them with a flange at the top. This complete insulation between the part *B* and the top *C* will completely cut off the electric current from passing down the pole, and thus prevent accidents. The top may be 85 constructed of such dimensions as to accommodate any desired number of cross-pieces and insulators for additional wires.

The advantages of my invention are that the lower part, being of cast-iron, has great 90 stiffness at the place where it is most needed, where it enters the ground, is of better material for receiving the grouting, thereby rendering the pole more stable, and is not liable to decay from rust, as wrought-iron is. The 95 wrought-iron or upper part combines great lightness with great strength, is more sightly than a solid pole, and makes the pole easily accessible for painting in all its parts, for repairs, and for the placing and arrangement 100 of the wires.

Having fully described my invention, what I claim therein as new, and desire to secure by Letters Patent, is—

1. A support for electric wires, composed of a cast-iron base, an open wrought-iron upper part, and a completely insulated top carrying insulators for such wires, and provided with means for tightening cross-wires, substantially as and for the purpose set forth.
2. A support for electric wires, composed of a cast-iron base, an open wrought-iron upper part, and a completely insulated top provided with means for tightening cross-wires, substantially as and for the purpose set forth.
3. In a support for electric wires, the combination of a cast-iron base and an upper part of wrought-iron composed of upright bars or rods connected by a bar running

angularly or spirally between them, substantially as and for the purpose set forth.

4. In a support for electric wires, the combination of an upper wrought-iron part composed of upright bars or rods, connected by a bar running angularly or spirally between them, and a top part completely insulated, substantially as and for the purpose set forth.

In testimony whereof I affix my signature in presence of two witnesses.

UDOLPHIO SNEAD.
